Columbus, Ohio, assignors to Westinghouse Electric
Corporation, a corporation of Pennsylvania

Filed June 30, 1966, Ser. No. 2,873

Term of patent 14 years

(Cl. D67—3)

FIG. 1.

FIG. 3.

FIG. 5.

FIG. 2.

FIG. 4.

FIGURE 1 is a perspective view of a refrigerator-freezer cabinet embodying our new design;

FIG. 2 is a front elevational view thereof;

FIG. 3 is a top plan view thereof;

FIG. 4 is a right side elevational view thereof; and

FIG. 5 is a fragmentary, enlarged cross-sectional view taken on line V—V of FIG. 2.

The rear wall not shown is conventionally plain.

The dominant feature of our design resides in the portions shown in full lines.

We claim:

The ornamental design for a refrigerator-freezer cabinet, substantially as shown and described.
